UNITED STATES PATENT OFFICE.

CYRIL E. BASTON, OF WILKINSBURG, PENNSYLVANIA, ASSIGNOR TO WESTINGHOUSE ELECTRIC & MANUFACTURING COMPANY, A CORPORATION OF PENNSYLVANIA.

REVERSIBLE CABLE-GUIDE BRACKET.

Application filed June 29, 1922. Serial No. 571,791.

My invention relates to cable-gathering devices, more especially to a guide bracket for guiding the cable as it is unreeled from or gathered by the winding drum.

- 5 It is among the objects of this invention to provide a guide bracket which shall be of simple construction, which shall be simple in its operation and easily manipulated without the use of tools by the operator.
- 10 It is a further object of this invention to provide a device of the above-designated character which shall function to guide the cable from either side of the reeling device without altering the position of the reel itself.

- 15 It is often desirable, as on mine locomotives, used in gathering service to provide an extension cable for use in connecting the driving motor to the trolley wire when operating from the main line where a trolley can not be used. In this kind of operation, it is sometimes necessary to operate from both sides of the main line and, to do this efficiently, it is necessary to provide means for 20 paying out and gathering the extension line from both sides of the reeling mechanism.

- 25 My invention is directed to a guide bracket which is reversible and permits operating the extension line or cable from either side of the locomotive.

In the accompanying drawings constituting a part hereof and in which like reference characters designate like parts,

- 30 Figure 1 is an elevational view of a reversible guide bracket made in accordance with this invention; and

35 Fig. 2 is an end view thereof showing the guide bracket secured to the main support of the reeling device.

- 40 The reversible guide bracket consists of a pair of supporting columns 1 forming an integral part of the drum support 2 which is mounted on a suitable base plate 3. A cross-rod 4 is rigidly secured between the 45 supports 1 and constitutes a guide rod for a guide bracket 5 which is movably mounted on a bushing 6. A double acting screw 7 is rotatably mounted in the supporting brackets 1 underneath the guide rod 4 parallel 50 therewith and is connected, through a gear train housed in the casing 8, to the driving mechanism of the drum 9.

55 The guide bracket 5 is provided with a plurality of stop lugs 10 co-operating with

stop member 10' to limit its angular movement on the bushing 6 and is further connected to the screw 7 by a loose fitting tongue 11 which seats in a nut 12 screwed into the bracket 5.

60 A guide bushing 13 of an insulating material, such as porcelain, having an opening 14 extending therethrough, is secured to the guide arm 5 by U-bolts 15. A sheave wheel 16 of insulating material is rotatably mounted on the bushing 6 and is provided 65 with a grooved periphery 17 in alignment with the opening 14 of the guide bushing 13. The guide bracket 5 is adapted to pivot on the cross rod 4 and may be in either position, as shown by the dotted lines, to provide 70 an unimpeded path for a cable 18 passing therethrough.

75 One end of the cable 18 is secured to a terminal 19 in alignment with a slip ring 20 mounted on the drum 9 from which the current is collected by brushes 21 connected to the terminal 19. The free end of the cable is attached to the trolley wire on the main line to establish a circuit between the power line and the driving motor. 80

85 My apparatus operates briefly as follows: The cable 18 is disposed in the groove 17 of the sheave wheel 16 and through the opening 14 of the guide bushing 13. In the winding of the cable through the guide bushing, the screw 7 is rotated, causing the guide bracket to move in a horizontal direction along the guide rod 4 to distribute the cable evenly on the face of the drum 9. Since the screw 7 has a left and right hand 90 thread, the tongue 11, held by the nut 12, follows each in turn back and forth along the guide rod 4, causing the cable to be wound in even layers on the drum.

95 If the cable 18 is to be distributed in the direction of the winding mechanism, the bracket 5 is turned 180 degrees, assuming a position indicated by the dotted lines. The guide bracket in either position rests against the stop 10' to locate the guide bushing 13 100 horizontally, either in its normal or in its reversed position.

105 The winding drum 9 is actuated by a motor mounted inside of the drum which is connected to the slip ring 20. A plurality of leads 22 (Fig. 1) are secured to the slip ring 20 and to the main driving motor (not shown).

It will be readily understood from the above description of my invention that a reversible cable guide bracket made in accordance therewith provides a simple and inexpensive device for cable-gathering reels where it is necessary to feed the cable in opposite directions at different times and that such a device provides a simple means for accomplishing a changeover in direction without the use of hand tools, or the like.

Although I have described a specific embodiment of my invention, it will be obvious to those skilled in the art that various modifications may be made in the details of construction thereof without departing from the principles herein set forth. For instance, the shape and general structure of the cable guide bracket may be varied in accordance with its function under various operating conditions. In place of the porcelain insulator, any suitable insulating material may be employed for the cable guide which may be secured to the guide bracket in any suitable manner.

I claim as my invention:

1. A cable guide comprising a pair of supporting brackets, a cross rod mounted thereon, a guide bracket having a guide bushing secured thereto movably mounted on said cross rod, a sheave wheel centrally and rotatably mounted in said guide bracket and means for moving said guide bracket angularly on said cross-rod to guide the cable over or under said sheave wheel.

2. A cable guide comprising a pair of supporting brackets, a cross-rod mounted thereon, a guide bracket having an insulating guide bushing secured thereto movably mounted on said cross arm, and a sheave wheel centrally and rotatably mounted in said guide bracket, said bracket being adapted to be pivoted through an angle of 180°.

3. A cable guide comprising a pair of supporting brackets, a drum rotatably mounted thereon, a cross rod secured to said brackets,

a guide bracket having a porcelain guide bushing secured thereto pivotally mounted on said cross rod, a sheave wheel centrally and rotatably mounted in said guide bracket, means for effecting lateral movement of said guide bracket on said cross rod, and means for disposing said bracket in such manner that the cable winding on or off said drum will pass over or under said sheave wheel.

4. A cable guide comprising a pair of supporting brackets, a cross rod mounted thereon, a guide bracket having a porcelain guide bushing secured thereto pivotally mounted on said cross rod, a sheave wheel centrally and rotatably mounted in said guide bracket and means for effecting lateral and pivotal movement of said guide bracket on said cross-rod.

5. A cable guide comprising a pair of supporting brackets, a cross-rod mounted thereon, a guide bracket provided with stop lugs for supporting it in a horizontal position and having an insulated guide bushing secured thereto movably mounted on said cross-rod, a sheave wheel centrally and rotatably mounted in said guide bracket and means for effecting lateral movement of said guide bracket on said cross rod and means for providing angular movement of a portion of said bracket between the limits of said stop lugs.

6. A cable guide comprising a pair of supporting brackets, a cross-rod mounted thereon, a guide bracket provided with stop lugs for supporting it in a horizontal position and having an insulated guide bushing secured thereto movably mounted on said cross-rod, a sheave wheel centrally and rotatably mounted in said guide bracket and means for effecting angular movement of said bushing relative to said cross-rod.

In testimony whereof, I have hereunto subscribed my name this 23rd day of June, 1922.

CYRIL E. BASTON.
